UNITED STATES PATENT OFFICE.

WILLIAM DAYTON HUNTER, OF ELIZABETHTON, TENNESSEE.

DESIGN FOR A COFFEE-POT.

SPECIFICATION forming part of Design No. 26,300, dated November 17, 1896.

Application filed September 24, 1896. Serial No. 606,892. Term of patent 14 years.

To all whom it may concern:

Be it known that I, WILLIAM DAYTON HUNTER, a citizen of the United States, residing at Elizabethton, in the county of Carter 5 and State of Tennessee, have invented and produced a certain new and original Design for Coffee-Pots; and I do declare the following to be a full, clear, and exact description of the invention, such as will enable others skilled in the art to which it appertains to 10 make and use the same.

My invention has relation to a design for a coffee-pot.

It relates to the entire configuration of the 15 pot.

My design relates particularly to the coffee-pot as illustrated in the accompanying drawings, in which—

Figure 1 is a perspective view of a coffee- 20 pot embodying my design, and Fig. 2 is a vertical section of the same.

Similar reference-numerals refer to similar parts in the different views.

The leading features of my design appear 25 in the following description.

1 represents a cylindrical chamber having

an approximately S-shaped flat handle 3 and a cylindrical tapering spout 2.

4 represents a vertical rectangular rib, plane on its upper end and beveled off on its 30 lower end, as shown in the drawings. Near the top of the chamber is a concave recess, groove, or bead extending entirely around the chamber in a horizontal plane. Near the bottom of the chamber appears an outwardly-projecting V-shaped rib extending in a horizontal plane around said chamber, as shown. 35

5 represents the convex-shaped top or cover, having a handle with a semicircular circumferential shank surmounted by an acorn-shaped knob, as shown in the drawings. 40

Having thus fully described my design, what I claim as new, and desire to secure by Letters Patent of the United States, is—

The design for a coffee-pot, substantially 45 as herein shown and described.

In testimony whereof I hereunto affix my signature in presence of two witnesses.

WILLIAM DAYTON HUNTER.

Witnesses:

C. P. CASS,
F. E. HUNTER.
